UNITED STATES PATENT OFFICE.

JOHN F. OHMER, OF DAYTON, OHIO.

MEANS FOR CHECKING COLLECTORS IN PUBLIC CONVEYANCES, &c.

SPECIFICATION forming part of Letters Patent No. 659,180, dated October 2, 1900.

Application filed December 9, 1899. Serial No. 739,768. (No model.)

To all whom it may concern:

Be it known that I, JOHN F. OHMER, residing at Dayton, in the county of Montgomery and State of Ohio, have invented certain new 5 and useful Improvements in a Means for Checking Collectors in Public Conveyances, &c.; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to a new and useful system for keeping account of fares collected in public conveyances and other details appertaining to the character of the service.

That the invention may be better understood I desire to say first that I disclaim any particular style of ruling or the adoption of any particular head-lines. My system being adapted to any railroad collecting various classifications of fares regardless of the number 25 of classifications, it is apparent that the headings and rulings must be made to conform to the operation of the various roads as the case may require.

I disclaim invention as to the taking of 30 readings of the register by the conductors. It is the general rule with all registers, so far as I have knowledge, that conductors take their own readings, from which they make up their own reports to the company. Having 35 access to these readings and having the duty imposed upon him of taking same and making up his own report with the systems in vogue, it is obvious that the conductor practically has control of the situation. For 40 instance, on a road collecting two or three or more fares and having a register with one series of register-wheels for the collection of all the fares or having duplicates of the register-wheels to register separately the various fares the conductor by taking his own 45 readings naturally makes his returns according to the readings taken.

One object of my invention is to take from the conductor the knowledge of the fares registered in their individual classification and at the same time provide a way by which receipts may be given from one conductor to

another, absolutely checking up the work of each as a whole and at the same time fixing responsibility of each for the separate classifications of fares collected, the access to which record is given to the office management only. With this system a conductor who is charged with having collected two hundred fares of various classifications and being aware of the 55 fact that the register-report will exhibit to the management in detail under each classification the two hundred fares collected cannot successfully manipulate the fares collected by him without detection. The consciousness on the part of the conductor of this fact will compel him to turn over to the company all the fares he has collected, and being responsible for all fares registered by him he will necessarily take from the relief conductor 60 a receipt, which will positively fix his own responsibility. The said receipt will be either for the total registration made of all fares collected by him at the time of his relief, as indicated by the passenger-indicator, or for the 65 trip completed by him at the time of relief, as indicated by the trip-indicator, which necessarily actuates with each impression taken 70 of the various fares registered.

It will not be necessary for impressions to 80 be made with the completion of each trip. The management may require conductors to combine two or more trips for each impression, in which case, as in all cases, the relieved conductor will take a receipt from his successor for the last impression made, be it for one trip only or for any number of trips combined, or he will take a receipt at the time of his relief for the total number of registrations made by him regardless of the number of trips. 85 In either event the responsibility of fares collected by the various conductors is fixed absolutely. 90

I do not limit my invention to any particular form of receipt for the total registration 95 made or for the trip upon which one conductor is relieved by another, as many forms may be used.

The further object of the invention is to provide a concise and accurate system for 100 keeping in detail form the fares collected by the conductors of street-cars, whereby any discrepancies or irregularities in the fares accounted for by said conductors are easily

ascertained, and for keeping a concise record of the efficiency of the service. It is particularly adapted for railway companies collecting two or more classifications of fares.

5 Preliminary to a detailed description of my improved system reference is made to the accompanying drawings, of which—

Figure 1 is a statement taken from a fare-register, upon which statement are shown in 10 five separate groups several classes of fares—for example, five-cent fares, three-cent fares, full tickets, &c. Such statement is taken at the close of the day's business or at such other time as may be desired by the management 15 of the company. This figure represents only ten trips of five classifications of fares. Fig. 2 is a form for use of conductor and subconductor at the time of relief of either by means of which a receipt is given to the conductor 20 so relieved for the trip or trips made by him at the time of his relief. As it is most desirable to relieve the conductor of as much clerical work as possible, thereby permitting him to devote his whole time to the taking 25 on of passengers and collecting fares, I have provided with my system forms whereby receipts may be given from one conductor to another for the trip or trips made by each, no pen or pencil of any kind being required. 30 Said form when used in combination with the print or impression will fix the responsibility of each conductor for the fares collected by each, respectively. Figs. 3 and 3^A are forms for the conductor's daily report, 35 upon which is noted the statement of the passenger-register, indicating the number of passengers carried and fares collected and the number of trips made, respectively. Figs. 4 and 4^A are forms for use of conductor and 40 subconductor at the time of relief by means of which the fares collected by each, regardless of their classification, are kept separate and distinct and upon which receipts are taken from one conductor to another. Figs. 45 5 and 6 are forms of receipts to the conductor and subconductor for the fares turned in by them at the close of the day's business or the end of a trip as the case may be. Fig. 7 is a form for detail entries of fares and other 50 data, as shown by the register statement, Fig. 1. Fig. 8 is a form for the monthly balances filled in from form shown in Fig. 7. Fig. 9 is a form for annual balances filled in from form shown in Fig. 8.

55 Referring to Fig. 1, A is a printed statement taken from the register at the close of each day's business (or at the end of any number of trips) and upon which a classified arrangement of fares registered. The number 60 of the trips, the day and month, as well as the number of the register, are indicated, B⁷ being the register-number in the present instance. The several kinds of fares are grouped or classified as follows: The column 65 A' indicates the five-cent fares; B, the three-cent fares; C, the full tickets; D, the half-tickets; E, the transfers. Each horizontal

row of the figures in said groups represents an impression comprising the total fares in each classification by the trip or at other intervals combining several trips, as the management may require. The figures to the right hand from "1" upward indicate the number of impressions or trips made. This statement A is not accessible to the conductor, although he may make the impression thereon. It is an independent statement showing each classification of fares, and by deducting one horizontal row from the row above the number of fares registered under each classification can be determined, or by deducting the first or lowest horizontal row from the last or top row the fares in detail under each classification can be determined for the length of time the car has operated since the last-printed statement was removed from the register. If one conductor only should operate the same register during the entire day, he would be responsible for all the fares registered in each classification and any irregularities would be determined by deducting the first and lowest horizontal row of figures (shown on Fig. 1) from the last and top row, as shown.

To ascertain the conductor's responsibility and the responsibility of others who operate the register during the day, Figs. 4 and 4^A are now brought into use. These forms are for keeping separate the work of the various conductors, and a copy of same is given each conductor, with the date, car-number or register-number, number of conductor, columns for indicating the number of trips, the register statement, passengers carried, time on, time off, and for the signature of the conductors and subconductors. It will be seen that the regular conductor completed his third trip with a total of one hundred and ninety-five fares collected and passengers carried up to and inclusive of said third trip. The relief conductor is now ready to take the car, and before doing so he takes the relief statement, Fig. 4, from the regular conductor and, observing that the trip-indicator connected with the register is at "4," he writes in the "Trip No." column on the relief statement "4." Observing the passenger-indicator at "195," he writes "195" on the relief statement in the column "Register statement." He notes his "time on" and signs his name as "sub 110 John L. Harries" in the signature-column and returns the statement, Fig. 4, to the regular conductor, which constitutes a receipt to the regular conductor for his work up to the time he is relieved from duty by the subconductor. At the same time the regular conductor may sign a similar "relief statement" to the subconductor. These receipts (or either of them) fix the responsibility of the subconductor absolutely, for he must account for all fares registered above one hundred and ninety-five or for all fares registered by the trip above and including trip No. 4 until he in turn is relieved. In this example upon com-

pletion of trip No. 4 the regular conductor returns to take his car. An impression on A is again taken, and with this impression the trip-number "5" is simultaneously printed 5 in the same line. Observing the trip-indicator at "5" and the passenger-indicator at "260," the conductor Chas. G. Gibson receipts to the subconductor for trip No. 5 and register statement "260," as shown on Fig. 4. 10 By so doing it makes the subconductor responsible for all fares collected on trip No. 4 or for all fares collected from one hundred and ninety-five to two hundred and sixty, which, as shown by the passenger-indicator 15 when taking and leaving the car, being a difference of sixty-five fares, is the number for which the sub must make returns to the company. Neither conductor has any knowledge in detail as to how many fares in each classification are necessary to make up the one hundred and ninety-five fares collected by 20 the regular conductor for trips Nos. 1, 2, and 3 or the sixty-five fares collected by the subconductor on trip No. 4, except as memory 25 may serve him.

Under this system each conductor will be expected to return all the cash, tickets, transfers, &c., collected by him—in short, to empty his pockets to the company after taking out 30 the change allowed him. The returns made separately by the several conductors are added together in their classified order, as per Figs. 5 and 6. It is found that the total cash returned is thirteen dollars and ninety-eight cents; full tickets, one hundred and eighty-five; half-tickets, twenty-one; transfers, two hundred and twenty-one. Taking 35 up the impression from the register, Fig. 1, we find by deducting the first from the last impression, beginning in the five-cent column A', "0439" from "0697" leaves two hundred and fifty-eight fares, which at five cents equals twelve dollars and ninety cents. In the second or three-cent column B, deducting "0028" 40 from "0064" leaves thirty-six fares, which at three cents equals one dollar and eight cents. Twelve dollars and ninety cents plus one dollar and eight cents equals thirteen dollars and ninety-eight cents, which is the amount 45 returned in cash by the several conductors. In the third column C deduct "0420" from "0605." The difference being one hundred and eighty-five, we find that one hundred and eighty-five full tickets were registered and returned by 50 the several conductors. Taking the next column D and deducting "0009" from "0031" we find the difference to be twenty-two fares, being the number of half-tickets registered; but the total half-tickets returned by the several 55 conductors being only twenty-one we note a discrepancy of one half-ticket, and the question now arises as to the responsibility for the one half-ticket which is short. The receipts taken by the conductors from one to 60 the other are indisputable as to which trips were operated by each or as to the statements of the passenger-indicator at the time of tak-

ing and leaving the car, or as to both, and it is only necessary to make the calculation from the impression or print taken from the register 70 A, Fig. 1, to fix the responsibility absolutely. The deduction made in the last or transfer column E shows a difference of "221," which is the number of transfers returned by the several conductors. The only discrepancy, 75 therefore, being in the half-tickets and with the knowledge that the subconductor operated the fourth trip the cashier or other person in authority refers to trip No. 4 in the half-ticket column D of the impression A, 80 Fig. 1, and finds "0015" at the beginning of trip No. 4 and "0019," a difference of four, at the finish of trip No. 4, which is, as a matter of course, the beginning of trip No. 5. The subconductor having previously reported 85 but three half-tickets, it is therefore obvious that the one half-ticket short was collected and registered by him on trip No. 4 and not reported. To locate this discrepancy by the passenger-register receipt, Fig. 4 shows the 90 subconductor registered sixty-five fares, beginning with the register statement at "195" and concluding with the register statement at "260." To reach the figures "195" on the impression statement A, Fig. 1, begin with 95 the first and lowest horizontal line and make deductions from the successive lines above until the total, "195," is reached, which in this case is the fourth line—viz, beginning in the five-cent column A', "0439" from "0520" equals 100 eighty-one; three-cent column B, "0028" from "0037" equals nine; full-ticket column C, "0420" from "0480" equals sixty; half-ticket column D, "0009" from "0015" equals six; transfer-column E, "0622" from "0661" equals 105 thirty-nine, making a total of one hundred and ninety-five. In the same manner it will be found that the total of "260" is in the fifth line, reached by deducting the first and lowest horizontal line from the figures in the fifth 110 line. Now deduct the figures in the fourth line from the horizontal line above and we get the following: Five-cent column A', "0520" from "0548" equals twenty-eight; three-cent column B, "0037" from "0040" equals three; 115 full-ticket column C, "0480" from "0499" equals nineteen; half-ticket column D, "0015" from "0019" equals four; transfer-column E, "0661" from "0672" equals eleven, making a total of sixty-five fares registered by the 120 subconductor while he had the car. His actual returns being only sixty-four, the discrepancy is easily located by the office.

The daily report, Fig. 3, can be used for convenience in noting from the indicator the trip or horizontal line on the impressed sheet, Fig. 1; but it is not absolutely necessary in any sense for locating discrepancies, as above described.

Upon the relief statement, Fig. 4, can be 130 noted the time on and time off when each conductor begins or leaves off his work, the receipts taken for which may be of great value to the company. It is not necessarily

essential to the system unless used to determine the trip upon which the conductor's responsibility begins or ends, for which purpose it might be used, as street-cars usually operate on schedule time. Forms Figs. 6 and 5 are filled out by the conductor and subconductor, respectively, previous to making their reports. The conductor notes in form Fig. 6 the number of trips operated by him—viz, "1" to "3" and "5" to "10," inclusive; his cash received—viz, twelve dollars and forty-nine cents; full tickets, one hundred and sixty-six; half tickets, eighteen; transfers, two hundred and ten, and passengers carried six hundred and fifty-seven, all of which cash, tickets, and transfers are turned over to the cashier, who receipts to the conductor for the fares turned in. The subconductor notes upon a similar form, Fig. 5, under the heading of "Trip No." the figure "4," which indicates that he operated trip No. 4. He also puts down "\$1.49" in the cash-column, "19" in the full-ticket column, "3" in the half-ticket column, "11" in the transfer-column, and "65" in the column headed "Passengers carried." These various collections are turned over to the cashier (or others in authority) and a receipt given for same, as in the case of the regular conductor. The conductors may then turn over these cashier's receipts to the auditor or other designated officer, and the cashier will be held responsible for such cash and other fares received by him. The conductors will also give up their relief statements at the time of turning over the fares. These various fares returned are now compared with the printed statement, Fig. 1, taken from the register to see if the proper returns have been made by the several conductors, the discrepancies, if any, being located, as stated heretofore.

The conductors have no access to the register statement. It is in no wise under their control, and if they should dare manipulate or juggle the fares the returns made by them will not agree with the register statement, Fig. 1, because of the physical impossibility of remembering the amount and number of fares collected, and the errors will immediately be detected and located.

Referring further to the register statement, Fig. 1, the bottom line of figures thereon indicates the statement of the register at the beginning of the day; the second line, the statement of the register at the beginning of the second trip; the third line, the statement of the register at the beginning of the third trip, and so on. The top line indicates the statement of the register at the close of the day, and the same figures will appear at the beginning of the next day's business. In order to ascertain the collections for any one trip, one line of figures is subtracted from the line above. By subtracting the bottom line of figures from the top line the collection of fares for the entire day may be ascertained. For example, to ascertain the amount

of cash collected on the car, having register B⁷ for comparison with the record as shown by the conductors' reports, form Figs. 6 and 5, the bottom line of figures is deducted from the top line in the vertical columns A' and B, Fig. 1, which will show two hundred and fifty-eight five-cent fares and thirty-six three-cent fares as having been collected or registered during the day's business, which will equal twelve dollars and ninety cents collected in five-cent fares and one dollar and eight cents in three-cent fares, making a total of thirteen dollars and ninety-eight cents, the amount of cash turned in by the two conductors as per their statements on forms Figs. 6 and 5. The full tickets (shown by vertical column C, form Fig. 1) are next ascertained. By subtracting "0420," the bottom figures, from "0605," the top line, a remainder of one hundred and eighty-five is obtained for the day's collection of full tickets, which tallies with the full-ticket statements of the conductors on forms Figs. 6 and 5. The half-tickets are next compared, being shown by the vertical column D, form Fig. 1. By subtracting "0009," the bottom line of figures, from "0031," the top line, a remainder of twenty-two is obtained, representing the half-tickets collected. This shows a discrepancy of one half-ticket between the register statement and the subconductor's statement on form Fig. 5. The transfers (shown in vertical column E, form Fig. 1) are next compared. By subtracting "0622," the bottom line, from the top line "0843" a remainder of two hundred and twenty-one will appear, which tallies with the conductor's statements of transfers on forms Figs. 6 and 5. By adding together the several remainders, indicating the various fares, the total will indicate the number of passengers as seven hundred and twenty-two, which corresponds with the figures given on conductors' reports, forms Figs. 6 and 5. By this comparison of the register statement with the conductors' statements an error has been disclosed in the conductors' returns and located to the subconductor in the returns of the half-tickets.

Fig. 2, used in combination with A, Fig. 1, is as follows: Before taking the car each conductor is supplied with form Fig. 2, upon which is noted the conductor's number, the number of the car, (to which is charged a specific register,) and date. The first conductor operates three trips, when the relief conductor takes possession of the car. Before doing so, however, the first conductor in the presence of the relief conductor makes an impression on the printed statement in the register, the said impression including the totals of the classified fares registered, the date, the number of the register, and the trip-number. It being the completion of trip No. 3, the imprint on the statement will be "4," which imprint "4" is exposed or indicated on the outside of the register by the

trip-indicator, the said indication being the only data exposed to the conductors from the printed statement in the register. The sub or relief conductor will then take the 5 form Fig. 2 from the preceding conductor and place his punch-mark in the column under heading of "Sub" and opposite trip No. 4, thereby receipting to the preceding conductor for trip No. 4. (See F, Fig. 2.) Returning 10 to the preceding conductor the form Fig. 2 the said preceding conductor may punch the form under the heading of "Con." and opposite trip "4," G, Fig. 2, which is an acknowledgment by him that he was relieved from 15 duty at the beginning of trip No. 4. Similar punches are made by one or both of the conductors on the form held by the subconductor, whereby the subconductor is charged with his responsibility at the beginning of trip 20 No. 4. The receipt taken by the conductor for trip No. 4 must of necessity record the totals of all fares collected by him, since all the totals must be impressed on the sheet simultaneously with the impression of the trip- 25 number. The subconductor in this case makes one trip only—viz., trip No. 4—when the preceding conductor returns to take the car, at which time another impression is made which exposed the trip-indicator at "5" and 30 the subconductor will punch the preceding conductor's form, Fig. 2, opposite trip five. (See H, Fig. 2.) The preceding conductor also punches his own form opposite trip "5 I," Fig. 2, which is an acknowledgment by 35 him that he assumed charge of his car beginning with trip No. 5. He will also punch the form held by the subconductor in a similar manner, and the sub may also punch his own form corresponding with the punches made 40 in the form of the preceding conductor. The regular conductor then continues his charge until completion of trip No. 10, as indicated by his own punch-mark "J," Fig. 2, at the beginning of trip No. 11. A similar punch- 45 mark opposite trip "1" denotes that the conductor began with trip No. 1. The forms held by each conductor are returned to the office with the fares of each. In this case the punch-marks on the conductor's form indicate 50 this responsibility for trips Nos. 1 to 3, inclusive, and from 5 to 10, inclusive, and the form turned in by the subconductor will fix his responsibility for trip No. 4. Discrepancies, if any, in the returns made by either 55 or both conductors are determinable by comparing the forms with the printed statement taken from the register A, Fig. 1.

Referring to Fig. 7, this is designed for the daily - service report for each car for the 60 month and shows the numbers of the conductor and motorman on duty each day, the fares collected and accounted for by the register when the car is taken out and turned in, the number of fares short or over, the mile- 65 age of the car, and the character of the service from day to day, as per printed headings thereon. One of these forms is used for each

car and contains an accurate and full report of the earnings of the car and its service. The number of the register—viz., "B"—the 70 number of the conductor "63," detail statements from the register, and other data showing the character of the conductor's service appear in a concise tabulated statement. These statements are taken by the accountant from register statement form Fig. 1. For example, referring to top line L, form Fig. 7, the register-number is "B". This register on the first day and first trip started under charge of conductor number "63" with 80 statement "0439" five-cent fares and ended the day with the statement of "0697," showing that a total of two hundred and fifty-eight fares of that class had been collected—the difference between the two sums—which 85 made a total of twelve dollars and ninety cents in money. The register statement thus corresponding with the conductor's returns, Figs. 6 and 5, there were no shorts or overs in the five-cent division. On the morning of the first 90 day the same register and same conductor start on the first trip with register statement "0028" and end with the statement "0064," showing that thirty-six total three-cent fares were collected, which amount to one dollar and 95 eight cents. This agreeing with the conductor's statements on forms Figs. 6 and 5 shows there were no discrepancies to note on form Fig. 7 in connection with the three-cent fares. Coming next to the full-ticket division on 100 form Fig. 7, on the morning of the first day the same register and conductor start on the first trip with the register statement "0420" and end with the statement "0605," showing that a total of one hundred and eighty- 105 five full tickets were collected, thus agreeing with the conductors' statements, forms Figs. 6 and 5. No shorts nor overs, therefore, were noted on form Fig. 7. Upon assorting these tickets it was found that fifteen were tickets 110 issued by the "John St. Line," forty-six were issued by the "Vine St. Line," and one hundred and twenty-four were issued by the "Eden Traction Line," which were accordingly recorded under the respective headings 115 on form Fig. 7. Coming next to the half-ticket division on form Fig. 7, on the morning of the same day the register statement at the beginning of the first trip indicated "0009" 120 and closed the day's business with the statement of "0031," showing a total of twenty-two fares of that series as having been collected. This register statement not agreeing with the conductors' statements on these fares on forms Figs. 6 and 5 (which show the 125 entry of twenty-one half-tickets) "1" is entered under the head of "Short" in the half-ticket division, form Fig. 7. This shortage of one half-ticket is further noted under the heading "3" in the "Merit" division and 130 under the heading "Good" in the same division, form Fig. 7. The "Merit" space has five vertical columns with the headings "4," "3," "0," "2," "1." The two columns "4"

and "3" on the left of the zero-mark are intended for the merit-marks. Those on the right of said zero-mark—viz., "2" and "1"—are for the demerit-marks. A shortage of a 5 half-ticket in an entire day's business not being considered an evidence of bad service the figure "1" is accordingly entered under the heading "3" to denote a good mark. If the 10 returns as made by the conductor were not at variance with the statement taken from the register, the conductor would be entitled to a mark in the first merit column "4" and also a mark of two good points in the column headed "Good." The entries for transfers are made in the same manner from form 15 Fig. 1 to form Fig. 7, and the number of miles is ascertained by multiplying the number of miles in one trip by the number of trips. A duplicate sheet, Fig. 7, may be 20 made for the record of the subconductor's work or a notation made under the head of "Remarks," Fig. 7, referring to any discrepancy or otherwise made by the subconductor.

For the monthly-balance entries on form 25 Fig. 8 a single horizontal line is all that is necessary for each car for the whole month. The permanent headings on this form are self-explanatory and are all above the first horizontal line K, upon which is noted the 30 statement of the earnings of car "148" for an entire month, the number of the conductor being "63." At the end of each month the various columns of figures are footed up on form Fig. 7 and entered in their 35 respective columns on form Fig. 8. For example, the total number of five-cent fares collected, ("6 00,") together with the cash (\$345) and the shorts and overs, "1" and "4," respectively, are entered on said form Fig. 8, 40 and the other classifications of fares are likewise footed up on form Fig. 7 and carried to form Fig. 8, together with the merit-marks.

At the end of each year's business an annual balance is had on form Fig. 9 by transferring the totals of each month from form 45 Fig. 8 to said form Fig. 9. Each horizontal line on the latter form is all that is required for the entry of a month's earnings and a record of the service for each month.

50 So far as is known, I am the pioneer inventor of a fare-register for several classifications of fares and with means for taking a print or impression statement at any time of the fares registered, and I believe I am the 55 first to invent the system whereby the responsibility for fares registered by the several conductors during the interval of time between one reading of the impressed statement and the next one taken can be fixed 60 without the positive knowledge by any of the conductors of the classified record of fares registered, and which will keep a detailed record of all the fares collected, noting the discrepancies and other data connected with 65 the service.

While this system is particularly adapted for street-car service, I realize that it may be

used for other purposes, as in stores or other places where registrations of business transactions are made.

Having described my invention, I claim—

1. In a system for keeping account of the fares collected by conductors in street-cars, a sheet provided with data recorded from time to time including a distinct impression or print taken from the register, said impression or print comprising a classified arrangement of fares registered, at the time of relief of each conductor in combination with a form to be used when one conductor is relieved from his charge by another, whereby a receipt can be given to the conductor so relieved, said form showing the number of passengers carried or total registrations made by the relieved conductor up to the time of his relief. 85

2. In a system for keeping account of the different fares collected in street-cars, an impression or print taken from the register comprising a statement showing in classified arrangement the different fares registered by the trip or for any number of trips combined in combination with a form to be used when one conductor is relieved by another, whereby a receipt can be given to the conductor so relieved, said form showing the particular 95 trip or group of trips made, by the relieved conductor, up to the time of his relief.

3. In a system for keeping account of the fares collected by conductors in public conveyances, a sheet provided with data recorded from time to time including a distinct impression or print taken from the register, said impression or print comprising a statement showing a classification of the different fares registered at the time of relief of each conductor in combination with a printed or written form whereby a receipt can be given to the conductor relieved from his charge, said receipt showing the number of trips made by the relieved conductor and also showing the 110 number of passengers carried.

4. In a system for keeping account of the fares collected by conductors in street-cars, a sheet provided with data recorded from time to time including a distinct impression or print taken from the register, said impression or print comprising a classified arrangement of fares registered at the time of relief of each conductor in combination with a form to be used when one conductor is relieved from his charge by another, whereby a receipt can be given to the conductor so relieved said form showing the number of passengers carried or total registrations made by the relieved conductor up to the time of his relief, and a printed or written form constituting a receipt to the conductor for cash fares and other classifications of fares reported by the conductor. 125

5. In a system for keeping account of the fares collected by conductors in street-cars, a sheet provided with data recorded from time to time including a distinct impression or print taken from the register, said impression or print comprising a classified arrangement

- of fares registered at the time of relief of each conductor in combination with a form to be used when one conductor is relieved from his charge by another, whereby a receipt can be given to the conductor so relieved said form showing the number of passengers carried or total registrations made by the relieved conductor up to the time of his relief, and a printed form upon which can be noted the fares as recorded by the register when the car is taken out and returned, and any discrepancies occurring between the fares as reported by the conductor and those appearing in the impressed statement of the register.
- 15 6. In a system for keeping account of the fares collected by conductors in street-cars, a sheet provided with data recorded from time to time including a distinct impression or print taken from the register, said impression or print comprising a classified arrangement of fares registered at the time of relief of each conductor in combination with a form to be used when one conductor is relieved from his charge by another, whereby a receipt can be given to the conductor so relieved said form showing the number of passengers carried or total registrations made by the relieved conductor up to the time of his relief, a printed form comprising a daily report showing the fares as recorded by the register when the car is taken out and returned, and any discrepancies occurring between the fares as reported by the conductor and those appearing in the impressed statement of the register, and a printed form comprising a monthly statement taken from said daily report.
7. In a system for keeping account of the fares collected by conductors in street-cars, a sheet provided with data recorded from time to time including a distinct impression or print taken from the register, said impression or print comprising a classified arrangement of fares registered at the time of relief of each conductor in combination with a form to be used when one conductor is relieved from his charge by another, whereby a receipt can be given to the conductor so relieved said form showing the number of passengers carried or total registrations made by the relieved conductor up to the time of his relief, a printed form comprising a daily report showing the fares as recorded by the register statement when the car is taken out and returned, and any discrepancies appearing between the fares as reported by the conductor and those appearing in the impressed statement of the register; a printed form comprising a monthly report of the totals of said daily report; and another printed form comprising an annual report of the totals of the monthly report.
8. In a system for keeping account of the different fares collected in street-cars, an impression or print taken from the register comprising a statement showing in classified arrangement the different fares registered by the trip or for any number of trips combined, in combination with a form to be used when

one conductor is relieved by another, whereby a receipt can be given to the conductor so relieved, said form showing the particular trip or group of trips made by the relieved conductor up to the time of his relief, and a printed form showing the fares as recorded by the register when the car is taken out and returned, and any discrepancies occurring between the fares as reported by the conductor and those appearing in the impressed statement of the register.

9. In a system for keeping account of the different fares collected in street-cars, an impression or print taken from the register comprising a statement showing in classified arrangement the different fares registered by the trip or for any number of trips combined, in combination with a form to be used when one conductor is relieved by another, whereby a receipt can be given to the conductor so relieved, said form showing the particular trip or group of trips made by the relieved conductor up to the time of his relief, a printed form comprising a daily report showing the fares as recorded by the register when the car is taken out and returned, and any discrepancies occurring between the fares as reported by the conductor and those appearing in the impressed statement of the register, and a printed form comprising a monthly report taken from the said daily report.

10. In a system for keeping account of the different fares collected in street-cars, an impression or print taken from the register comprising a statement showing in classified arrangement the different fares registered by the trip or for any number of trips combined, in combination with a form to be used when one conductor is relieved by another, whereby a receipt can be given to the conductor so relieved, said form showing the particular trip or group of trips made by the relieved conductor up to the time of his relief, a printed form comprising a daily report showing the fares as recorded by the register statement when the car is taken out, and returned, and any discrepancies occurring between the fares as reported by the conductor and those appearing in the impressed statement of the register, a printed form comprising a monthly report of the totals of said daily report, and another printed form comprising an annual report of the totals of said monthly report.

11. In a system for keeping account of fares collected in street-cars and of the character of the service, an impression or print taken from the register comprising a statement showing in classified arrangement the different fares registered by the trip or for any number of trips combined in combination with a form whereby a receipt can be given to the conductor relieved from his charge, said receipt showing the particular trip or group of trips made by the relieved conductor, and also showing the number of passengers carried; and a printed form showing the fares as recorded by the register when the car is taken

out and returned and any discrepancies occurring between the fares as reported by the conductor and those appearing in the impressed statement of the register.

- 5 12. In a system for keeping account of fares collected by conductors in street-cars, and the like, an impression or print taken from the register comprising a statement showing a classified arrangement of the fares registered by the trip in combination with a form to be used when one conductor is relieved by another conductor, said form showing the number of the trip at which the first conductor is relieved and the next conductor begins, and 15 the number of the trip upon which the second conductor is relieved.
13. In a system for keeping account of fares collected by conductors in street-cars, and the like, an impression or print taken from the 20 register comprising a statement showing a classified arrangement of the fares registered by the trip in combination with a form to be used when one conductor is relieved by another conductor, said form showing the

number of passengers carried by the first conductor up to the time of his relief.

14. In a system for keeping account of the fares collected by conductors in street-cars, a sheet provided with data recorded from time to time including a distinct impression or print taken from the register, said impression or print comprising a classified arrangement of fares registered at the time of relief of each conductor in combination with a form to be used when one conductor is relieved from his charge by another, whereby a receipt can be given to the conductor so relieved said form showing the number of passengers carried or total registrations made by the relieved conductor up to the time of his relief, and a form 35 upon which is noted the number of trips made and the number of passengers carried.

In testimony whereof I affix my signature in presence of two witnesses.

JOHN F. OHMER.
